MANUFACTURE OF MOTOR FUEL FROM
SLUDGE OILGeorge Armistead, Jr., Lockport, Ill., and Walter
Ullrich, Port Arthur, Tex., assignors to The
Texas Company, New York, N. Y., a corpora-
tion of Delaware

Application July 8, 1931, Serial No. 549,568

11 Claims. (Cl. 196—50)

This invention relates to the manufacture of cracked motor fuel by the thermal conversion of oil recovered from sludge obtained in the refining of hydrocarbon oils.

5 The invention contemplates a process for the manufacture of motor fuel of high anti-knock qualities comprising distilling crude petroleum for the production of lubricating oil stock, treating the resulting stock with strong mineral acid 10 to remove therefrom, in the form of a sludge, hydrocarbon constituents unsuitable for lubricating purposes, treating the sludge to separate therefrom hydrocarbon oil which is subjected to partial distillation to form a stock substantially 15 free from mineral acids and adapted for cracking, and then subjecting the separated hydrocarbons to cracking under suitable conditions for the production of cracked motor fuel.

Lubricating oil containing fractions, and more 20 particularly heavy or residual fractions of the cylinder stock type, as obtained from crude petroleum, usually contain substantial proportions of unsaturated and tarry-like constituents whose presence is unsuitable in finished lubricating oils and which are, therefore, removed 25 from the lubricating oil fractions in the form of a sludge during subsequent treatment with a strong mineral acid. This sludge, composed largely of polymerized, sulphonated and 30 oxidized hydrocarbons, has been, in the past, after separation therefrom of dilute acid, disposed of as fuel or utilized to some extent in the production of certain types of asphaltic material.

The prior art has also included treatment of 35 this sludge material by first neutralizing its acidic bodies with lime and then reducing the neutralized sludge to coke by destructive distillation. The distillate resulting from this method of treatment is composed substantially of hydrocarbons of the boiling range of gas oil or 40 higher while the resulting coke on account of its lime content is unsatisfactory for fuel purposes.

However, this sludge material, when properly 45 conditioned to free it of undesirable mineral acidic constituents and other corrosive substances as well as the relatively more coke like components is particularly suitable for cracking for the production of high-grade motor fuel possessing high anti-knock qualities.

50 Our process, therefore, comprises distilling crude oil for the production of a lubricating oil fraction, such as cylinder stock, and which may comprise either a residual stock, such as obtained by ordinary distillation at atmospheric pressure, or, on the other hand, a distillate stock obtained

by distilling crude at subatmospheric pressures. The resulting lubricating oil stock is then subjected to treatment with strong mineral acid to remove tarry and unstable hydrocarbon constituents as a sludge which may comprise as much as 30 to 40 per cent or even more of the original lubricating oil stock. This sludge may then be mixed with a substantial proportion of water which latter serves as a medium for washing out the retained and partially spent acid and, in 10 addition is mixed with a relatively large quantity of gas oil or other hydrocarbon oil, suitable as a diluent, for cutting back and increasing the fluidity of the sludge undergoing treatment.

5 This resulting mixture is then subjected to 15 cooking and steaming to resolve the sludge into a substantially fluid condition and facilitate separation therefrom of liquid hydrocarbons, accompanied also by a separation of aqueous and acidic material, during subsequent settling. The separated liquid hydrocarbons obtained during the settling step may then be subjected to cracking advantageously under super-atmospheric pressures ranging as high as 400 pounds or more, at 20 temperatures which may range from 750° to 950° 25 F. or higher and then fractionating the resulting cracked products to recover the cracked gasoline constituents.

25 By way of illustrating in greater detail the process of carrying out our invention, crude petroleum, for example, of the type obtained in the mid-continent fields, is distilled, preferably at 30 substantially atmospheric pressure, to remove its low boiling constituents which may include gasoline, kerosene, gas oil and wax distillate, and form 35 a residual cylinder stock fraction which latter may comprise from 25% to 30% of the original crude and have a viscosity of from 100 to 130 Saybolt Universal seconds at 210° F.

40 This cylinder stock fraction is introduced to an agitator wherein it may be agitated with from about 35 to 50 pounds per barrel of 98° Bé. sulphuric acid, the amount of the acid required depending upon the desired characteristics of the 45 final lubricating oil product. The acid treatment may extend over a period of 45 minutes while maintaining the mixture at a temperature of around 110° F. for example. Following this, the acid-treated oil is permitted to settle for several hours to effect complete separation of 50 the particles of sludge from the treated oil.

45 After removal of the acid-treated oil, the remaining sludge is mixed with water and a diluent gas oil in approximately the proportion of 3 parts of sludge with 1 part of water and 2 parts 55

of gas oil. The mixture of sludge, oil and water is then subjected to cooking by the introduction of open steam, the cooking operation being carried out at a temperature of around 220° F. and extending over a period which may range from 8 to 24 hours, after which the mixture is allowed to settle and form two layers. The upper layer comprises liquid hydrocarbons separated from the sludge in admixture with the diluent gas oil 10 and containing small amounts of acid. The bottom layer is composed of a mixture of heavy coke-like sludge particles, water and spent acid.

After removal of the upper layer, the remaining bottom layer, after drawing off the separated aqueous portion, is advantageously subjected to further dilution, including, if desired, neutralization with alkaline material and then cooking in substantially the same manner as in the preceding step for the purpose of separating additional liquid hydrocarbons from the sludge and which hydrocarbons are added to the hydrocarbon mixture at first separated. Repetition of this dilution and cooking treatment may be carried out to whatever extent necessary in order to effect 25 the desired degree of liquid hydrocarbon recovery. The total recovered liquid hydrocarbons may comprise from around 60% to 70%, or even more, by volume of the original sludge.

The heavy sludge or coky material remaining from the cooking operation is not particularly desirable for commercial cracking since it is not only of a very coky nature and therefore productive of a large amount of coke but it also retains a considerable amount of acid and acid 35 compounds which, if not removed, would be injurious to the distilling and cracking equipment. When subjected to cracking temperatures, decomposition of these compounds or salts may occur with the liberation of acidic matter, such 40 as sulphur dioxide, for example.

The mixture of recovered liquid hydrocarbons and diluent gas oil usually retains small amounts of acidic material, which, unless removed or further suitably treated, would exert an injurious 45 effect upon the cracking apparatus. Therefore, we remove these acidic or corrosive constituents by first subjecting the hydrocarbon mixture to a preliminary distillation wherein the aqueous material is volatilized and any salt compounds, decomposable on heating, may also be broken down 50 to liberate acidic matter, all of which is removed along with a small amount of relatively low boiling hydrocarbon constituents, serving as a stripping medium. This distillate is advantageously 55 removed and condensed in the presence of an alkaline material, such as lime, soda ash or caustic, and the like, to neutralize its corrosive effect and thus protect the still equipment. The amount of hydrocarbon constituents removed in 60 this operation may be varied at will.

Thus, if desired, substantially all of the diluent oil may be removed in this operation and returned to recycle through the system as further diluent for fresh sludge. It is advantageous, however, 65 to leave the bulk of this diluent oil, which is itself suitable for cracking, in admixture with the recovered oils, removing just sufficient to effect complete stripping out of the acidic material. This latter operation is of particular advantage where the diluent gas oil comprises a 70 recycle gas oil consisting of the cracked hydrocarbons resulting during the subsequent cracking operation and which are of relatively higher boiling point than that desired for the desired 75 cracked gasoline product. The resulting par-

tially distilled hydrocarbon oil mixture, substantially free from acidic material, is then subjected to cracking advantageously in cracking apparatus of the coil and drum type wherein it is heated to a temperature of around 900° F. and under a pressure of from 100 to 250 pounds. The particular operating temperatures and pressures employed may be varied, depending upon the nature of the particular stock, or upon the degree to which it has been reduced in the preliminary distilling operation. Thus, if only a small portion of the diluent and relatively more refractory gas oil and lighter hydrocarbon constituents have been removed in this preliminary distillation operation, the subsequent cracking operation may 15 be carried out at relatively high temperatures and pressures, whereas if the stock has been reduced so as to remove substantially all of the diluent gas oil added thereto during the initial treatment of the sludge, then the cracking temperatures and pressures may advantageously be modified to somewhat lower values.

The stock, particularly where the greater portion of the diluent gas oil has been removed, and comprises hydrocarbons from which carbon may 20 be readily deposited on the interior surfaces of heating coils, may be suitably cracked in coil and drum cracking apparatus wherein the fresh charge is brought into contact with a generated stream of cracked vapors, thereby vaporizing its 25 gas oil constituents which, together with partially converted and more refractory fractions, form a clean stock comparatively free from constituents rich in carbon and, therefore, adapted 30 for circulation through the cracking coil at relatively high temperatures without substantial coke formation.

The resulting cracked products are fractionated, preferably while under pressure derived 40 from the cracking reaction, to separate the desired cracked gasoline components, while the heavier fractions are returned to the coil for further heating. The pressure tar formed during this operation is subjected to a stripping action in the manner customarily employed in 45 regular cracking operations to remove, besides gasoline constituents, the heavier and intermediate constituents or recycle gas oil. All or a portion of this recycle gas oil may be used as 50 a diluent or solvent in the initial treatment of the acid sludge to prepare fresh cracking stock therefrom. That portion not used in treating the sludge may be returned directly to the cracking apparatus.

When cracking under substantially the foregoing conditions, a stock of around 14° Bé. gravity and having a viscosity of 700 seconds at 55 122 Saybolt Furol, a cracked gasoline fraction of around 410 end point may be obtained having an anti-knock value of 68 expressed in terms of 60 octane numbers.

While cracking may be effected at superatmospheric pressures, as above described, it is contemplated that the recovered hydrocarbons, either with or without having first removed the 65 diluent gas oil, may be subjected to destructive distillation in a shell type of still maintained under substantially atmospheric pressure to produce a cracked fraction and coke. This cracked fraction may then be fractionated to remove its 70 gasoline constituents and form a gas oil fraction which is suitable for further cracking under pressure.

In the drawing the single figure represents diagrammatically an oil treating system embodying 75

my invention. Referring more particularly to the drawing reference numeral 1 indicates a crude still into which oil to be treated may be charged through pipe 2. Three (3) indicates a fire box 5 for supplying the necessary heat. In the still the oil is heated to such a temperature that the lighter fractions thereof pass off as vapors through line 4 into any suitable fractionating equipment 5, the amount of oil so vaporized being sufficient to leave 10 in the still 1 a lubricating oil fraction, which may be for example, of the cylinder stock range of viscosity. Where the fresh oil charge to the still is a crude petroleum, for example, of the type obtained in the mid-continent fields, the residual stock remaining in the still 1 after removal of the lighter fractions may comprise from 25 to 15 30% of the original charge and have a viscosity of from 100 to 130 Saybolt Universal seconds, at 210° F., the lighter fractions distilled off, including 20 gasoline, kerosene, gas oil and wax distillate. The residual oil is drawn off through line 6 having therein a cooler 7 and is introduced by pump 8 into the top of an agitator 9. In this agitator reaction of the oil with strong mineral acid, introduced through line 10, takes place. This acid may be, for example, 98° Baumé sulphuric acid, the amount of acid used being, for example, from 35 to 50 pounds per barrel of oil. After acid treatment for a period of, for example, 45 minutes, at 30 a temperature of around 110° F. the acid treated oil is permitted to settle for several hours, to effect complete separation of the particles of sludge from the treated oil. The acid treated oil comprising the top layer, indicated by reference numeral 11, 35 may be drawn off through a line 12 while the heavy sludge is transferred through line 13 into tank 14.

Water and diluent gas oil are introduced into the tank 14 through lines 15 and 16 respectively, 40 the oil serving to dilute the sludge and the water to wash the acid therefrom. The mixture of sludge oil and water is then subjected to cooking by the introduction of open steam through line 17, the cooking operation being carried out at a 45 temperature of around 220° F. and extending over a period which may range from 8 to 24 hours, after which the mixture is allowed to settle and form two layers. The upper layer 18 comprises liquid hydrocarbons separated from the sludge in 50 admixture with diluent gas oil and contains small amounts of acid. The bottom layer 19 is composed of a mixture of heavy coke-like sludge particles, water and spent acid. Twenty (20) indicates a separated aqueous portion consisting of 55 water and the acid washed out thereby. The aqueous portion, and the heavy sludge or coky material remaining from the coking operation, may be withdrawn from the tank 14 through drawoff line 21, while the mixture of recovered 60 liquid hydrocarbons and diluent gas oil, which usually retains small amounts of acidic material, is drawn off through the line 22 and is subjected to distillation, for example in the shell still 23, heated by a furnace 24. In this still the temperature of the liquid hydrocarbons is first raised 65 sufficiently to volatilize and distill off any aqueous material contained therein and also to remove any salt compounds which are decomposed by the heating and broken down, thereby liberating acidic material. A small amount of relatively 70 low boiling constituents are also distilled off, thus serving as a stripping medium. These distilled products pass off through pipe 25 and condenser 26 wherein they may be condensed and neutralized 75 by the addition of lime, soda ash, caustic or the

like through line 28, the condensate being collected in receiving drum 27. When operating in this manner valve 66 is closed and valve 65 open. Any desired portion of the resulting condensate may be returned to the tank 14 through line 29, 5 by action of pump 30, any remainder being diverted from the process through pipe 31. After the preliminary distillation of acidic material from the liquid hydrocarbons in the still 23 the remaining, substantially acid free, oil may be removed through line 32 having valve 32' and pump 33 for introduction into a first fractionating column 34 of a cracking system indicated generally by reference numeral 35. Condensate is removed from the bottom of the fractionator 34 and returned through pipe 36 having pump 37 into still 38, while light vapors pass overhead from the fractionator 34 entering the second fractionator 39 wherein they undergo a further partial condensation. Light vapors of products suitable for 10 use as motor fuel pass overhead through line 40 then through condenser 41 into receiving drum 42, while reflux condensate-collecting in the bottom of the fractionator 39 and constituting a clean cracking condensate, is withdrawn through conduit 43 and forced by pump 44 through cracking heater or furnace 45, wherein it is heated to an effective cracking temperature, which may be for example around 900° F., the pressure on the products passing from the heater being, for example, 20 for 100 to 250 pounds per square inch. The highly heated products are then passed through the pipe 46 into the still 38, wherein a cracking temperature is maintained and further cracking occurs. 30

Liquid residue produced in still 38 may be drawn off from time to time or continuously through drawoff line 47, and passed through reducing valve 48 into flash drum 49. In the flash drum light products separate, as vapors, from heavy liquid residue, these vapors passing off through 40 vapor line 50 into fractionator 51. Gasoline constituents pass off as vapors from the fractionator through line 52, for any further treatment desired, for example they may be condensed in condenser 53, the condensate being collected in receiver 54. Reflux condensate, which is removed through line 55, may be passed, by pump 70, through pipe 16, into the tank 14 to be used as diluent or solvent oil in the initial treatment of the acid sludge to prepare fresh cracking stock 50 therefrom, in the manner explained hereinbefore. The remaining portion not so used may be returned through conduit 56, to the cracking process. Heavy liquid residue may be drawn off from 55 the flash drum 49 through pipe 57.

Instead of being transferred to the cracking unit 35, the recovered hydrocarbons withdrawn from tank 14 may be subjected to destructive distillation in the still 23, either with or without prior removal of the diluent gas oil, under substantially atmospheric pressure to produce a cracked fraction and coke. This cracked fraction may then be fractionated in fractionator 60 to remove its gasoline constituents which pass off through vapor line 61 and condenser 62 into receiver 63, 60 and form a gas oil fraction which is suitable for further cracking under pressure. This gas oil fraction may be withdrawn through line 64, as reflux condensate, and introduced into line 32 for cracking in the cracking system 35. In this case 65 valve 65 would be closed and valve 66 open.

Obviously, for continuous operation, several agitators 9 and settling tanks 14 may be provided so that while some of them are being permitted 70 75

to settle, others may be used for mixing fresh charges.

If desired the wax distillate or other lubricating oil fraction from fractionator 5 may be treated 5 as described hereinbefore, this fraction being transferred to line 6 through conduit 67. Oil may be diverted from the process through valved pipes 68 and 69 whenever desired.

Obviously, many modifications and variations 10 of the invention, as hereinbefore set forth, may be made without departing from the spirit and scope thereof, and therefore only such limitations should be imposed as are indicated in the appended claims.

15 We claim:

1. A method of producing cracked motor fuel of high anti-knock properties which comprises distilling crude petroleum and forming therefrom a lubricating oil fraction of the cylinder stock 20 range of viscosity, subjecting the fraction to treatment with strong mineral acid and thereby producing a heavy sludge containing polymerized, sulphonated and oxidized hydrocarbons, mixing approximately three parts of the sludge with approximately one part of water and two parts of 25 gas oil, subjecting the mixture to cooking in the presence of open steam to facilitate separation of liquid hydrocarbons and aqueous material from the sludge, permitting the cooked mixture to settle and separating therefrom liquid hydrocarbons suitable for cracking and comprising around 30 60% of the original sludge, subjecting the separated hydrocarbons and diluent oil to preliminary distillation to remove retained acidic material and 35 a substantial portion of the diluent gas oil, which is returned for treating further sludge, subjecting the remaining oil composed substantially of recovered sludge oil to continued and destructive distillation at relatively higher temperature and 40 then fractionating the resulting cracked product to produce motor fuel.

2. A method of producing cracked motor fuel of high anti-knock properties which comprises distilling crude petroleum and forming therefrom 45 a lubricating oil fraction of the cylinder stock range of viscosity, subjecting the fraction to treatment with strong mineral acid and thereby producing a heavy sludge containing polymerized, sulphonated and oxidized hydrocarbons, mixing approximately three parts of the sludge with approximately one part of water and two parts of 50 gas oil, subjecting the mixture to cooking in the presence of open steam to facilitate separation of liquid hydrocarbons and aqueous material from the sludge, permitting the cooked mixture to settle and separating therefrom an upper layer of 55 liquid hydrocarbons suitable for cracking, subjecting the separated hydrocarbons and diluent oil to preliminary distillation to remove retained acidic material and produce a substantially mineral acid-free cracking stock, subjecting said stock, while still retaining heat from said distillation, to cracking under superatmospheric pressure and at temperatures of over 750° F. and 60 then fractionating the cracked products to produce motor fuel.

3. A method of producing cracked motor fuel of high anti-knock properties which comprises distilling crude petroleum and forming therefrom 70 a lubricating oil fraction of the cylinder stock range of viscosity, subjecting the fraction to treatment with strong mineral acid and thereby producing a heavy sludge containing polymerized, sulphonated and oxidized hydrocarbons, steam- 75 ing the sludge in the presence of water and dilu-

ent gas oil to facilitate separation of liquid hydrocarbons and acidic material from the sludge, permitting the cooked mixture to settle and separating therefrom an upper layer of liquid hydrocarbons suitable for cracking, subjecting the separated hydrocarbons and diluent oil to distillation to remove retained acidic material and produce a substantially mineral acid-free cracking stock, subjecting said stock, while still retaining heat from said distillation, to cracking under superatmospheric pressure and at temperatures of over 750° F. and then fractionating the cracked products to produce motor fuel.

4. A method of producing cracked motor fuel of high anti-knock properties which comprises 15 distilling crude petroleum and forming therefrom a lubricating oil fraction of the cylinder stock range of viscosity, subjecting the fraction to treatment with strong mineral acid and thereby producing a heavy sludge containing polymerized, 20 sulphonated and oxidized hydrocarbons, diluting said sludge with recycle gas oil formed during subsequent cracking, adding water and subjecting the mixture to cooking in the presence of open steam to facilitate separation of liquid hydrocarbons and aqueous material from the sludge, permitting the cooked mixture to settle and separating therefrom an upper layer of liquid hydrocarbons suitable for cracking, subjecting the separated hydrocarbons and diluent oil to distillation 25 to remove retained acidic material and produce a substantially mineral acid-free cracking stock, subjecting said stock, while still retaining heat from said distillation, to cracking under superatmospheric pressure and at temperatures of over 30 750° F., fractionating the cracked products to produce motor fuel, and returning a portion of the relatively high boiling cracked products as a recycle gas oil for diluting further sludge.

5. A method of producing cracked motor fuel 40 of high anti-knock properties which comprises distilling crude petroleum and forming therefrom a lubricating oil fraction of the cylinder stock range of viscosity, subjecting the fraction to treatment with 98% sulphuric acid and thereby 45 producing a heavy sludge containing polymerized, sulphonated and oxidized hydrocarbons, mixing approximately three parts of the sludge with approximately one part of water and two parts of 50 gas oil, subjecting the mixture to cooking in the presence of open steam, permitting the mixture to settle and form an upper layer comprising recovered liquid hydrocarbons and diluent gas oil, and a bottom layer composed largely of heavier coke-like hydrocarbons, water and dilute mineral 55 acid, removing the upper layer, subjecting the bottom layer after removal of the separated aqueous material to further dilution and cooking to recover additional liquid hydrocarbons which are mixed with the hydrocarbons first removed, subjecting the mixture of recovered hydrocarbons and diluent gas oil to distillation to remove retained acidic material and produce substantially mineral acid-free cracking oil stock, while still 60 retaining heat from said distillation, subjecting said stock to cracking under pressures of the order of 100 pounds per square inch or higher and at a temperature of over 750° F. and then fractionating the cracked product to produce motor 65 fuel.

6. The method of producing cracked motor fuel of high anti-knock properties which comprises distilling crude petroleum and forming therefrom 70 a lubricating oil fraction of the cylinder stock 75

- range of viscosity, subjecting the fraction to treatment with strong mineral acid and thereby producing a heavy sludge containing polymerized, sulphonated and oxidized hydrocarbons, mixing 5 approximately three parts of the sludge with approximately one part of water and two parts of gas oil, subjecting the mixture to cooking in the presence of open steam to facilitate separation of liquid hydrocarbons and aqueous material from the sludge, permitting the cooked mixture to settle and separating therefrom liquid hydrocarbons suitable for cracking and comprising around 60% of the original sludge, subjecting the separated hydrocarbons and diluent oil to preliminary 10 distillation to remove retained acidic material and a substantial portion of the diluent gas oil, which is returned for treating further sludge, subjecting the remaining oil composed substantially of recovered sludge oil to continued and destructive distillation at relatively higher temperature to produce coke and vapors, fractionating said vapors to separate therefrom gasoline constituents and a gas oil fraction and cracking said gas oil fraction under pressure. 15
7. The method of producing cracked motor fuel from acid sludge produced by the treatment of a hydrocarbon lubricating oil fraction with a strong mineral acid, which comprises mixing said sludge with a diluent oil to reduce the viscosity thereof so that it may be settled into layers, mixing water with the diluted sludge and cooking the mixture by direct contact with steam to facilitate separation of liquid hydrocarbons and aqueous material from the sludge, permitting the cooked mixture to settle and separate into an upper layer of liquid hydrocarbons, and a lower layer of heavy sludge or coky material having an aqueous portion, removing liquid hydrocarbons from said layer first mentioned, subjecting the removed liquid hydrocarbons to preliminary heating to distill therefrom retained acidic material and a portion of said diluent oil, subjecting remaining oil to cracking conditions of temperature and pressure to cause cracking thereof, and fractionating the resulting cracked vapors to produce motor fuel. 25
8. A method according to claim 7 wherein a relatively light oil derived from said liquid hydrocarbons is utilized as diluent for additional acid sludge. 30
9. The method of producing cracked motor fuel from acid sludge produced by the treatment of a hydrocarbon lubricating oil fraction with a strong mineral acid, which comprises mixing said sludge with a diluent oil to reduce the viscosity thereof so that it may be settled into layers, mixing water with the diluted sludge and cooking the mixture by direct contact with steam to facilitate separation of liquid hydrocarbons and aqueous material from the sludge, permitting the cooked mixture to settle and separate into an upper layer of liquid hydrocarbons, and a lower layer of heavy sludge 35
- or coky material having an aqueous portion, removing liquid hydrocarbons from said layer first mentioned, subjecting the removed liquid hydrocarbons to preliminary heating to distill therefrom retained acidic material and a portion of said diluent oil, subjecting remaining oil to destructive distillation to produce a cracked fraction and coke, and fractionating said cracked fraction to separate gasoline constituents therefrom. 40
10. A method of producing cracked motor fuel of high anti-knock properties which comprises distilling crude petroleum and forming therefrom a lubricating oil fraction of the cylinder stock range of viscosity, subjecting the fraction to treatment with strong mineral acid and thereby producing a heavy sludge containing polymerized, sulphonated and oxidized hydrocarbons, mixing with the sludge a substantial proportion of water and a relatively large quantity of diluent gas oil, subjecting the mixture to cooking in the presence of open steam to facilitate separation of liquid hydrocarbons and aqueous material from the sludge, permitting the cooked mixture to settle and separating therefrom liquid hydrocarbons suitable for cracking and comprising around 60% of the original sludge, subjecting the separated hydrocarbons and diluent oil to preliminary distillation to remove retained acidic material and a substantial portion of the diluent gas oil, which is returned for treating further sludge, subjecting the remaining oil composed substantially of recovered sludge oil to continued and destructive distillation at relatively higher temperature and then fractionating the resulting cracked product to produce motor fuel. 45
11. A method of producing cracked motor fuel of high anti-knock properties which comprises distilling crude petroleum and forming therefrom a lubricating oil fraction of the cylinder stock range of viscosity, subjecting the fraction to treatment with strong mineral acid and thereby producing a heavy sludge containing polymerized, sulphonated and oxidized hydrocarbons, mixing with the sludge a substantial proportion of water and a relatively large quantity of diluent gas oil, subjecting the mixture to cooking in the presence of open steam to facilitate separation of liquid hydrocarbons and aqueous material from the sludge, permitting the cooked mixture to settle and separating therefrom an upper layer of liquid hydrocarbons suitable for cracking, subjecting the separated hydrocarbons and diluent oil to preliminary distillation to remove retained acidic material and produce a substantially mineral acid-free cracking stock, subjecting said stock, while still retaining heat from said distillation, to cracking under superatmospheric pressure and at temperatures of over 750° F. and then fractionating the cracked products to produce motor fuel. 50
